(57) **CLAIM**

The ornamental design for a luminaire, as shown and described.

DESCRIPTION

FIG. 1 is a perspective view of a luminaire showing my new design;

FIG. 2 is a bottom plan view thereof;

FIG. 3 is a top plan view thereof;

FIG. 4 is a front elevational view thereof;

FIG. 5 is a rear elevational view thereof;

FIG. 6 is a left side elevational view thereof;

FIG. 7 is a right side elevational view thereof; and,

FIG. 8 is an additional perspective view of the luminaire shown in an alternative configuration of use.

The broken line disclosure represents portions of the luminaire which form no part of the claimed design. The dash-dot-dash broken line disclosure define a claim boundary and form no part of the claimed design. The luminaire is shown with a symbolic break in its length. The appearance of any portion of the luminaire between the break lines forms no part of the claimed design.
